LIQUID COOLING OF HIGH TEMPERATURE BODIES

Charles V. Litton, Redwood City, Calif., assignor to International Standard Electric Corporation, New York, N. Y., a corporation of Delaware

Application October 5, 1942, Serial No. 460,800

15 Claims. (Cl. 250—27.5)

This invention relates to liquid cooling of high temperature body with specific relation to the cooling of vacuum tube anodes.

This invention is a continuation-in-part of my copending applications Ser. No. 429,871, filed February 7, 1942, and Ser. No. 446,034, filed June 6, 1942.

In the art of cooling hot bodies by a liquid in either direct or indirect contact therewith, the fact that the temperature of the body in contact with the cooling liquid should not be higher than the boiling point of the cooling liquid seems either to have been, in many cases, entirely disregarded, or if this fact has been recognized, the workers in the art have turned to other cooling media, such as air. Obviously, if the temperature of the hot body in contact with the liquid cooling medium is above the boiling point of that medium, there will not be liquid contact along the surface of the hot body, but rather a contact, for example, of vapor or vapor bubbles. This immediately disrupts the cooling effect of the liquid and, in a sense, one might say that liquid cooling is no longer present.

It is the primary object of the present invention to provide proper and efficient cooling of hot bodies by means of liquid, retaining all of the advantages of liquid cooling while eliminating obvious disadvantages and still efficiently cooling hot bodies whose radiant surface temperature is above the boiling point of the cooling liquid.

The above mentioned and further objects and advantages of my invention and the manner of attaining them will be more fully explained in the following description taken in conjunction with the accompanying drawings. In the drawings

Fig. 1 is a vertical cross-sectional view illustrating a finned liquid-cooled anode with a cooling arrangement formed in accordance with the basic principles of the present invention;

Fig. 2 is a partial horizontal cross-sectional view taken along the line 2—2 of Fig. 1 and drawn to a larger scale, showing the arrangement of fins in accordance with the present invention;

Fig. 3 is a vertical cross-sectional view of a modified form of cooling means for a vacuum tube anode;

Fig. 4 is a partial horizontal cross-sectional view taken along the line 4—4 of Fig. 3 and drawn to a larger scale;

Fig. 5 is a vertical, cross-sectional view of a vacuum tube anode cooled in accordance with a still further arrangement;

Fig. 6 is a partial enlarged horizontal cross-

sectional view taken along the line 6—6 of the arrangement illustrated in Fig. 5;

Fig. 7 is a vertical, broken, cross-sectional view of a still further modified arrangement for the cooling of a vacuum tube anode;

Fig. 8 is a partial enlarged horizontal cross-sectional view of the arrangement illustrated in Fig. 7;

Fig. 9 is a vertical, broken, cross-sectional view of a cooling arrangement for a vacuum tube anode, involving both longitudinal and annular cooling fins;

Fig. 10 is a partial enlarged horizontal cross-sectional view taken along the line 10—10 of the arrangement illustrated in Fig. 9;

Fig. 11 is a vertical, broken, cross-sectional view of an additional modified cooling arrangement for vacuum tube anodes; and

Fig. 12 is an enlarged, partial, horizontal cross-sectional view taken along the line 12—12 of the arrangement illustrated in Fig. 11.

A cooling system in its simplest form is illustrated in Figs. 1 and 2, showing an arrangement for cooling the anode 10 forming part of the envelope of a vacuum tube 11. In the case of such a tube, it may be necessary to dissipate a heat of 2000 watts per square inch of anode surface, and it will be assumed, for purposes of explanation, that the highest temperature, at which the tube can be operated without injury, is with an anode surface temperature of 320° C. The maximum water temperature, however, for efficient cooling purposes would be 100° C., representing a temperature difference of 220° C. If anode 10 is surrounded by a tubular member 12 having attached to its inner surface a plurality of longitudinally circumferentially spaced, fins 13 extending inwardly to contact the surface of the anode, the temperature of the anode will tend to drive the heat outwardly along these fins toward tubular member 12. By choosing fins of proper width the circumferential area about their outer edges may be so increased that the resultant heat to be dissipated from the effective radiating surface (previously taken as 2000 watts per square inch at the surface of the anode) will be reduced to 500 watts per square inch, equivalent to a temperature of 100° C. The fins may then be cooled by means of a suitable water jacket formed of a casing 14 enclosing tubular member 12 but in spaced relation thereto, the water jacket having an inlet 15 and an outlet 16. With this arrangement, in no case will the cooling water come in contact with metal above 100° C., and thus the water cooling

55 will be wholly efficient. The temperature gra-

dient of 220° between the anode surface and the metal in contact with the cooling water will insure that the heat is conducted outwardly from the anode surface to the cooling jacket. It is to be noted, in this connection, that if a finned anode were merely plunged into water, such temperature gradient would not exist, and the heat would not be driven outwardly. Structurally speaking, the arrangement in Figs. 1 and 2 is quite similar to that shown in my co-pending application Ser. No. 429,371.

Another embodiment of the invention is shown diagrammatically in Figs. 3 and 4. Anode 30 of tube 31 is shown enclosed in a cooling arrangement comprising fins 33 engaging the surface of the anode. The outer edges of the fins are encircled by one or more coils of tubing for a cooling fluid. A single coil 34 is shown in the drawings having an inlet 35 and an outlet 36. The helical cooling coil is utilized in somewhat the same manner as shown in my co-pending application 446,034.

To assist in the cooling action, I have also provided in this form of invention a suitable annular header 37 which is adapted to throw a fine spray downwardly along the fins 33 through suitable nozzles or openings 38. By using this arrangement the temperature at the outer edges of fins 33, in contact with the cooling tube 34 may be less than 100° C., so that one cooling tube will suffice. The use of the spray over the fins 33 merely permits that advantage be taken of the latent heat of evaporation of the water falling over the hot fins. The main cooling, however, is still done by the liquid in tube 34, and the basic principles of the present invention, namely, utilizing the temperature gradient through the fins to drive the heat outwardly and to limit the temperature of the fins in contact with the cooling medium to 100° C., or less, is still maintained.

Another embodiment of the invention is illustrated in Figs. 5 and 6 in which anode 50 of tube 51 is shown diagrammatically in a cooling arrangement including a plurality of fins 52. The fins and associated equipment in this embodiment as well as the others in the present application will be understood to be assembled and supported by any suitable arrangement, the details of which will be understood by those skilled in the art.

In the form of invention shown in Figs. 5 and 6, the longitudinal fins 52 have been widened, as compared to the type of construction illustrated in Figs. 1 to 4, inclusive, to such an extent that the heat to be dissipated at the outer edges of these fins will be in the vicinity of 65° C. The fins are then cooled by a plurality of sets of vertical tubes 55, 57, 58. The inlet tubes 56 are preferably connected together at one end by suitable means, such as the inlet header 59. The cooling water then flows upwardly through these tubes, is returned through the individual return tubes 57, whence it again flows upward through the tubes 58 to provide further cooling of the fins. The ends of tubes 58 may be connected together in an outlet header 60, from which the water is then drawn away. If the arrangement is properly designed, the temperature of the fins in the vicinity of the inlet tubes 56, will be approximately 65° C., and the water flowing through the tubes 56 will reach this temperature at the end of the tubes. This temperature will be maintained in the tube 57, but in the outlet tube 58, adjacent which the fin temperature is approximately 100° C., the water will be still further heated and will leave the outlet header at a temperature preferably just

below its boiling point. It will again be seen that in the form of invention illustrated in Figs. 5 and 6 the principle of providing a temperature gradient throughout the length of the fins 52 has been retained, while, again, the temperature of the fins in contact with the cooling liquid is never above the boiling point of the cooling liquid.

Figs. 7 and 8 show another form of the invention in which anode 70 of tube 71 is enclosed in a cooling arrangement in which a plurality of longitudinal fins 72 project from the inner surface of a casing 74 and contact the anode 70. On the outside of casing 74 is a second set of fins 75. These fins, for maximum efficiency should be of triangular cross-section as shown in Figure 8. Each fin is slotted, and in the present embodiment, three sets of cooling pipes, 76, 77 and 78 are disposed in each slot. The corresponding pipes in each fin are connected to common headers, pipes 76 being connected between headers 80 and 81; 77 between headers 82 and 83 and the innermost pipes 78 are connected between headers 84 and 85. Beyond the edges of the fins 75, the lower header 80 for the outer row of pipes is connected to the upper header 83 for the middle row or pipes 77 by a series of small pipes 86. Likewise, lower header 82 for the middle row of pipes is connected by pipes 87 to the upper header 85 for innermost pipes 78. An inlet for cooling fluid is shown at 88 connected to header 81 and an outlet 89 is shown connected to header 84. Instead of numerous small pipes 86 and 87 interconnecting the headers, single pipes of sufficient capacity could be used, provided the proper direction of flow of the cooling liquid is maintained, which is indicated by arrows in the drawings.

Fins 75 are proportioned preferably so that the change in cross-section through which the heat is transmitted is closely proportional to the amount of heat to be transmitted, so that the temperature of the fins drops off linearly outwardly. The direction of the flow of the cooling fluid is the same in tubes 76, 77 and 78, tube 76 being the coolest, while 78 is the hottest.

Construction of the arrangement just described would be simplified if fins 75 were of rectangular instead of triangular cross-section. Some loss in efficiency would result, but if the fins were properly proportioned, effective cooling could be accomplished. Preferably, in this case, the thickness of the fins should be about two thirds of their width.

Still another form of the invention is illustrated in Figs. 9 and 10 which show the anode 90 of a tube 91 disposed within a cooling apparatus comprising a casing 92 from the inner surface of which fins 93 project and contact anode 90. On the outside of casing 92 a plurality of helical fins 94 are formed or attached by any suitable method. Fins 94 may be of oblong cross section as shown in Fig. 9 or they may be of a slotted triangular cross-section as shown in Fig. 8. The embodiment as shown in Fig. 9 contemplates twelve or fifteen fins, though any suitable number may be used, between which are disposed an under layer of cooling tubes 95 and an upper layer 96. A header 97 to which the upper ends of tubes 96 are connected individually in spaced circumferential relation is provided with an inlet pipe 98. The lower ends of the tubes in this layer are similarly connected to a header 99 which in turn is connected for example, by a pipe 100 to header 101 at the upper part of the cooling device. Tubes 95 of the lower layer are connected in the manner described between header 101 and a lower header

102 which is provided with an outlet pipe 103. As in the previous embodiments fins 93 provide a temperature gradient between anode 90 and casing 92 the latter being cooled by the water cooling arrangement which produces a temperature gradient in outer fins 94.

The arrangement shown in Figs. 9 and 10 provides a way by which small tubes may be used to effectively conduct a large volume of cooling fluid so that the desired number of gallons per minute 10 may be forced through the tubes.

While the above embodiments of the invention have been generally described as using water for cooling a heated body which has a temperature insufficient to cause the cooling fluid to boil and thus lose its efficiency, it will be apparent that the various cooling systems of the invention, particularly those shown in Figs. 3 to 10 will operate successfully at temperatures considerably higher than that at which water normally boils. This is because the resistance to the formation of steam bubbles is greater in applicant's structure than in the well-known water jacket. Steam bubbles, in order to form, must displace an equal volume of water. In the conventional water jacket this merely pushes the water around to the other side of the anode. In the present invention, in order for steam to form, each bubble must give a large velocity increase to a long column of water flowing through a small tube with considerable friction, consequently, a temperature considerably above boiling point is required to overcome the effective pressure of the water in the tubes before steam bubbles will form.

In Figs. 11 and 12 another modification of the invention is illustrated adapted for cooling with a liquid such as "Prestone" in place of water permitting a higher liquid contact temperature. The anode 110 of tube 111 is enclosed in a relative thick sleeve 112 of a suitable heat conducting metal contacting with its inner surface anode 110 and having formed on or secured to its outer surface a single helical fin 113. Between the convolutions of the fin are, for example three layers of tubing 114, 115, 116 for the cooling fluid. The fluid is fed in through inlet 117 at the bottom of the outer layer 116 of tubes, and is led by an external pipe 118 to the lower part of the middle layer 115 and from the top of the middle layer by external pipe 119 to the bottom terminal of inner layer 114, the top part of which is connected to output pipe 120. The metal sleeve 112 in this case provides the necessary heat gradient between the surface of the anode and the spirally positioned cooling fins.

The embodiment shown in Figs. 11 and 12 may be modified so as to carry a greater volume of cooling fluid by using a parallel spiral tube arrangement as shown in Fig. 9 but with a cooling fluid such as "Prestone" fewer pipes in parallel would be required.

Other modifications of the invention will occur to those skilled in the art without departing from the spirit of the invention as described in the following claims.

What is claimed is:

1. An arrangement for cooling a hot body by a liquid, which comprises a plurality of fins disposed around said body having a temperature gradient thereacross, means for increasing the temperature gradient for said fins which comprises means for spraying water thereon in such volume that the water is immediately converted into steam, and further cooling means for said fins comprising tube means disposed about the 75

edges thereof remote from said body through which a cooling liquid flows.

2. A cooling arrangement for electron tubes and the like comprising a plurality of heat conducting fins disposed to conduct heat from the surface of the tube to be cooled, a plurality of rows of pipes for a cooling liquid disposed between the respective fins near the edges thereof remote from said tube, said fins being so proportioned that the heat gradient thereof conducts insufficient heat to the innermost row of pipes to boil the liquid therein and conduit means for interconnecting the respective rows of pipes so that the fluid flowing through the respective rows becomes progressively cooler toward the edges of said fins remote from said tubes.

3. A cooling arrangement according to claim 2 in which said conduit means are arranged to interconnect the respective rows of pipes so that the cooling fluid of all rows flows in the same direction.

4. A cooling arrangement according to claim 2 in which two pipes are provided between the respective fins, one pipe being connected to the other by a conduit beyond said fins and in which the outer pipes are all connected to a common header from which cooling fluid flows, and the inner pipes to a common outlet header.

5. A cooling arrangement for electron tubes and the like comprising a casing adapted to substantially enclose the part of the tube to be cooled, a plurality of heat conducting fins extending from the inner surface of said casing to the surface of the tube, a plurality of rows of fins on the outer surface of said casing, a plurality of layers of pipes between the last mentioned fins through which a cooling fluid flows, a common header for opposite terminals of the pipes in the respective rows, and conduit means for interconnecting the respective layers of pipes so that a heat gradient is maintained across each of the last mentioned fins.

6. A cooling arrangement according to claim 5 in which the fins on the outer surface of said casing 45 having a triangular cross-section, each fin being slotted, said layers of pipes being disposed in the slots.

7. A cooling arrangement according to claim 5 in which the cooling fins on the outside of said 50 casing are formed in a spiral with a plurality of layers of spiral cooling pipes disposed therebetween.

8. A cooling arrangement for electron tubes and the like comprising a sleeve surrounding the tube to be cooled, said sleeve being of sufficient thickness to cause a desired temperature gradient between the tube and outer surface of the sleeve, a plurality of fins arranged to cool the outer surface of said sleeve, a plurality of layers of pipes 60 for a cooling fluid in contact with said fins and means to interconnect the respective layers of pipe to a source of cooling fluid so that a temperature gradient is maintained in said fins.

9. A heat conducting support for an electron tube comprising a heat conducting sleeve construction including a plurality of fins at least partly separated from one another fitting the anode end of the tube, said fins extending radially outwardly to an outer surface of sufficient area to maintain a temperature below the boiling point of water, and a water cooling system associated with said outer surface comprising a plurality of adjacent runs of heat conducting water pipe interconnected to form a continuous water 70 circulating system.

10. A heat conducting support as set forth in claim 9, in which the water pipe is arranged as a continuous helix in contact with said surface.
11. A heat conducting support as set forth in claim 9, in which said outer surface is provided with a helical fin, and the water pipe is in the form of a continuous helix located between runs of said fin.
12. A heat conducting support for an electron tube comprising a heat conducting sleeve construction fitting the anode end of the tube and extending radially outwardly to an outer surface of sufficient area to maintain a temperature below the boiling point of water, and a water cooling system associated with said outer surface comprising a plurality of superposed cooling units, each unit including a plurality of adjacent runs of heat conducting water pipe interconnected to form a continuous water circulating system, said units being connected in series and provided with a water inlet in the outer unit and a water outlet in the inner unit.
13. A heat conducting support as set forth in claim 12, in which each unit includes a header at each end.
14. A heat conducting support as set forth in claim 12, in which each unit comprises helically arranged pipe runs extending around said outer surface.
15. A heat conducting support as set forth in claim 12, in which said outer surface includes a helical fin and each unit includes a helical pipe located between runs of said fin.

CHARLES V. LITTON.
